UNITED STATES PATENT OFFICE.

FRANKLIN WILMER WARD, OF NEW YORK, N. Y., ASSIGNOR TO UDALL AND BALLOU, OF NEW YORK, N. Y., A CORPORATION.

DESIGN FOR A RING.

No. 39,851.

Specification for Design.

Patented March 2, 1909.

Application filed November 16, 1908. Serial No. 462,986. Term of patent 7 years.

To all whom it may concern:

Be it known that I, FRANKLIN WILMER WARD, a citizen of the United States, residing at No. 215 West One Hundred and Eighth street, borough of Manhattan, city, county, and State of New York, have invented a new, original, and ornamental Design for Rings, of which the following is a specification, reference being had to the accompanying drawing, forming part hereof.

Figure I is a side view of a ring, showing part of my new design. Fig. II is a front

view of a ring, showing part of my new design. Fig. III is a side view of a ring, showing part of my new design. Fig. IV is a top view of a ring, showing part of my new design.

I claim:

The ornamental design for a ring, as shown.

FRANKLIN WILMER WARD.
